UNITED STATES PATENT OFFICE.

JOHN F. BENSON, OF PORTSMOUTH, VIRGINIA.

TRAVERSE-MACHINE.

Specification of Letters Patent. Patented Dec. 12, 1916.

1,208,459.

Application filed January 31, 1916. Serial No. 75,342.

To all whom it may concern:

Be it known that I, JOHN F. BENSON, a citizen of the United States, and a resident of Portsmouth, in the county of Norfolk and State of Virginia, have invented a new and Improved Traverse-Machine, of which the following is a full, clear, and exact description.

My invention relates to a machine particularly adapted for mechanically performing certain computations necessary in the calculation of the area of land from field notes of the survey.

The object of the invention is to provide an automatic, simple and efficient computing machine of the character stated with which the latitude and departure of any course may be obtained at one setting.

In its simplest form it consists of a protractor, distance indicator and registering wheels coöperating with the distance indicator and adjustable in a predetermined relation on the distance indicator by the movement of the protractor.

With the above and other objects in view, the nature of which will more fully appear as the description proceeds, the invention consists in the novel construction, combination and arrangement of parts as herein 30 fully described, illustrated and claimed.

In the accompanying drawings, forming part of the application, similar characters of reference indicate corresponding parts in all the views.

Figure 1 is an isometric view of my machine in its simplest form, certain parts not forming part of the invention having been omitted to simplify the disclosure; Fig. 2 is a plan of the machine; Fig. 3 is a front elevation; Fig. 4 is a horizontal section on line 4 4, Fig. 3; and Fig. 5 is a horizontal section on line 5 5, Fig. 3.

Referring to the drawings, 6 is the base of the machine, of any suitable material and convenient form. The protractor 7 is pivotally mounted on the base 6 to swing in a horizontal plane. A vernier 8 is provided for the divisions of the protractor so that any angle between zero and 90° may be read to single minutes. The micrometer screw for facilitating an accurate setting is omitted for the sake of simplification. The

protractor 7 is provided with an arm 9 in the plane of the protractor. A stud 10 is formed on the arm adjacent the end of the 55 arm. The stud 10 projects through the slots of a pair of crossing arms 11 and 12 forming part of slides 13 and 14 respectively. The two slots are at right angles to each other.

The slide 13 has an extension 15 engaging a socket 16 provided on the base which guides the slide in its movement when the same is displaced by the movement of the protractor. The slide 14 has a similar extension 15 also engaged in the socket 16 provided on the base for the purpose of guiding said slide when displaced by the protractor. Each of the slides is provided with a rigid upright or standard 17. Each standard has a lateral socket 18 engaged by a guiding rod 19. The outer end of each guide rod is secured to a corresponding lug 20 forming an integral part of the base, the inner ends of said rods being secured to a 75 bearing block 21 carried by a bearing frame 22 which is rigidly connected to the base 6.

A distance indicator 23, in the shape of a disk, is mounted to revolve on the bearing block 21 in a horizontal plane. The center 80 of rotation of said disk is in alinement with the intersection of the central lines of the slides 13 and 14. The rotary motion of the disk 23 is imparted to registering wheels 24 and 25 mounted to revolve in vertical 85 planes and having a frictional engagement with said disk. The two wheels are disposed at right angles to each other, each bearing in a corresponding frame 26 hinged to the corresponding standard 17, the weight carried by the frames helping to maintain the frictional engagement between the registering wheels and the disk. It will be noted that each of the recording wheels revolves in a vertical plane at right angles to the 95 direction of motion of the corresponding slide. The translatory motion imparted by the protractor to the registering wheels causes them to move along radial lines on the disk and at right angles to their planes 10 of revolution, consequently, such motion will not cause them to revolve.

It will be seen that when the protractor is at zero (see Fig. 4) the cross arm 12 will

aline with the slide 13. As the protractor moves from zero to 90° the stud 10 will move in an arc $a b c$; and when it is at 90° the arm 11 will aline with the slide 14, the 5 stud coinciding with the point c . When the protractor is at an angle d , as shown in Fig. 4, then

$$10 \quad \frac{oa'}{ob} = \cos. d \text{ and } \frac{oc'}{ob} = \sin. d.$$

Consequently when the cos. is zero the 10 cos. wheel, that is the registering wheel 24, which participates in the movement of the slide 13 will be in the center of the disk 23, 15 while the sin. wheel, which is the registering wheel 25 will be at the margin of the disk (see Fig. 1). Reversely, when the sin. is zero the registering wheel 25 will be in the center of the disk, while the registering 20 wheel 24 will be at the margin of the disk. Any intermediate relation between the sin. and cos. will maintain the wheels 24 and 25 on the disk in the relation of said units. If R be the distance of the stud 10 from the 25 axis of rotation o of the protractor, then R would be the maximum distance through which the registering wheels will move from the center of revolution of the distance indicator 23. When one of the registering 30 wheels is at maximum distance from the center of the disk and the disk is revolved, the locus of the point of contact between the said registering wheel and the disk will be a circumference having a radius ' R '. The 35 length of the circumference is then equal to $2\pi R$. With the registering wheels at any other position, the length of the circumferential path of the registering wheel will be proportional to the distance of the registering 40 wheel from the center of the disk. For instance, the registering wheel 24, as shown in Fig. 2, travels on a circumference the length of which is equal to $2\pi R \cos. d$ and equals the length of the maximum circumference times $\cos. d$. If we divide the length 45 of the maximum circumference into one hundred equal parts the disk can then be turned through any desired fractional part of a revolution, or through any number of 50 complete revolutions and a part of a revolution. The registering wheels are divided to measure off exactly the length of the circumferential path on the disk which passes under them. Thus, with the registering wheel 55 at maximum distance from the center of the disk the registering wheel will register one hundred for a complete revolution of the disk.

Suppose it is desired to obtain the latitude 0 and departure of the course N 54° W 231 feet, the protractor 7 is set at 54° . This automatically moves the registering wheel 24 into such position that its distance from the center of the disk equals R times $\cos. 54^\circ$, and the measuring wheel 25 into such a

position that its distance from the center of the disk equals $R \sin. 54^\circ$. As one revolution of the disk represents 100, the disk is turned 2.31 revolutions. The length of the maximum circumferential path on disk 23 70 passing a given point will be equal to $2 \times 3.1416 \times R \times 2.31$, which equals 231 divisions on the disk 23. The length of any smaller circumferential path of radius r , measured to the same scale, passing a given 75 point is $2 \times 3.1416 \times r \times 2.31$ and will be equal to

$$\frac{r}{R} \times 231.$$

In the problem, the path of the wheel 24 80 will have a radius of $R \times \cos. 54^\circ$. Therefore the distance over the circumferential path traveled by the wheel 24 will be equal to

$$231 \times \frac{R \cos. 54^\circ}{R} = 231 \times \cos. 54^\circ. \quad 85$$

But the latitude of a course is equal to the length of the course multiplied by the cos. of the bearing. Therefore the distance registered by the wheel 24 will be the latitude 90 of the given course. Similarly, the distance registered by the wheel 25 will be the departure of the given course.

The distance indicator 23 is provided with 95 a vernier 27 so that it can be set to .001 of its circumferential length. In addition, a revolution indicator 28 is mounted on the bearing frame 22 which is in mesh with a pinion mounted to revolve with the distance 100 indicator 23 and whereby the number of revolutions made by the distance indicator is registered on the revolution indicator. The revolution indicator is in the shape of a disk the margin of which is divided into 105 100 parts, each part representing one revolution of the distance indicator.

The registering wheels 24 and 25 have a diameter equal to one-half of the diameter 110 of the disk 23. They are divided into 50 equal parts. A vernier 29 is provided for each of the registering wheels reading to .1 of the smallest division. A worm 30 is constrained to rotate with each of the registering wheels. A worm wheel 31 is driven by 115 each of the worms, which wheel is mounted in the corresponding frame 26. A disk 32 and a pinion 33 are constrained to rotate with each of the worms. A similar disk 34 is rotatably mounted in each of the frames 120 26. A gear 35 constrained to rotate with the disk 34 is in mesh with the corresponding pinion 33. The disks 32 are divided into twenty parts, while the disks 34 are divided into ten parts. The ratio of the 125 worm wheel to the worm is 20, while the ratio of the gear 35 to the pinion 33 is 10. To facilitate the reading on the disks 32 and 34 an indicating bracket 36 is secured to the frame 26. The mechanism for setting 130

the machine to zero has been eliminated, as not forming part of the invention and to render the structure of the device plainer.

I claim:

- 5 1. In a machine of the class described a protractor having an arm mounted to turn in a horizontal plane, slides disposed at right angles and each having a slotted arm at right angles to the slide, said arms crossing each other, a stud on the protractor arm engaging the slotted arms of the slides, a standard on each slide adapted to participate in the movement thereof, a disk mounted to revolve in the horizontal plane 10 on an axis passing through the intersection of the center lines of the slides, a frame on each standard in pivotal engagement therewith, the force of gravity tending to move the frames toward the disk, a registering wheel in each frame mounted to revolve in the frame at right angles to the direction of motion of the corresponding slide, each of said wheels having a frictional engagement with the disk, means for registering the 15 number of revolutions made by the disk, and means for registering the number of revolutions of each registering wheel carried by the corresponding frame of the wheel.
2. In a machine of the class described, a protractor having an arm mounted to turn in a horizontal plane, slides disposed at right angles to each other and each having a slotted arm at right angles to the corresponding slide, said arms crossing each other, a 20 stud on the protractor arm engaging the slotted arms of the slides, the axis of movement of said protractor passing through the intersection of the center lines of the slides, a standard for each slide adapted to participate in the movement of the corresponding slide, a disk mounted to revolve in the horizontal plane on an axis coinciding with the axis of the protractor, an arm on each standard in pivotal engagement therewith so that 25 the force of gravity tends to move the frames toward the disk, a registering wheel in each frame mounted to revolve in a plane at right angles to the direction of motion of the corresponding slide, each of said 30 wheels having a frictional engagement with the disk, means for registering the number of revolutions of said disk, and means for registering the number of revolutions of each wheel.
3. In a machine of the class described a protractor mounted to turn in a horizontal plane, a distance indicator mounted to revolve in the horizontal plane, registering wheels mounted to revolve in vertical planes 35 and engaging frictionally the distance indicator, gravitationally operable means carrying said registering wheels whereby the registering wheels are engaged frictionally with the distance indicator, and motion transmission means from the protractor to 40

said gravitationally operable means whereby said registering wheels are displaced in a predetermined relation on said distance indicator.

4. In a machine of the class described, a protractor mounted to turn in a horizontal plane, a distance indicator mounted to revolve in the horizontal plane, registering wheels mounted to revolve in vertical planes and in frictional engagement with the distance indicator, motion transmission means from the protractor to the wheels for displacing said wheels on the distance indicator to and from the axis of rotation of said indicator, said motion transmission means including means whereby when one of said wheels is moved toward the axis of rotation, the other wheel is moved away therefrom. 75
5. In a machine of the class described, a protractor mounted to turn in a horizontal plane, a disk mounted to revolve in the horizontal plane and coaxial with the protractor, said disk having means for indicating distance, registering wheels mounted to revolve in a vertical plane and frictionally engaging the disk, a gravitationally operable frame for each of said registering wheels whereby the frictional engagement is maintained between the registering wheels and the disk, motion-transmission means from the protractor to the frames whereby the registering wheels are caused to move radially on the disk when the protractor is turned, said motion-transmission means including means whereby one of the wheels is caused to move toward the center of rotation of the disk, while the other is moved away therefrom, means for indicating the 80 number of revolutions of the disk, and means for indicating the number of revolutions of each of the registering wheels. 90
6. In a machine of the class described, a protractor mounted to turn in a horizontal plane, a disk mounted to revolve in the horizontal plane and co-axial with the protractor, said disk having means for indicating distance, registering wheels mounted to revolve in vertical planes and frictionally engaging the disk, the diameter of the registering wheels bearing a predetermined ratio 95 to the diameter of the disk, a gravitationally-operable frame for each of said registering wheels whereby the frictional engagement is maintained between the registering wheels and the disk, said registering wheels having divisions on the periphery thereof corresponding to the divisions of the disk, a vernier for said registering wheels carried by the corresponding frame, motion-transmission means from the protractor to 100 the frames whereby the registering wheels are caused to move radially on the disk when the protractor is turned, said motion-transmission means including means whereby one of the wheels is caused to move toward the center of rotation of the disk, while the other is moved away therefrom, means for indicating the number of revolutions of the disk, and means for indicating the number of revolutions of each of the registering wheels. 105
7. In a machine of the class described, a protractor mounted to turn in a horizontal plane, a disk mounted to revolve in the horizontal plane and co-axial with the protractor, said disk having means for indicating distance, registering wheels mounted to revolve in vertical planes and frictionally engaging the disk, the diameter of the registering wheels bearing a predetermined ratio 110 to the diameter of the disk, a gravitationally-operable frame for each of said registering wheels whereby the frictional engagement is maintained between the registering wheels and the disk, said registering wheels having divisions on the periphery thereof corresponding to the divisions of the disk, a vernier for said registering wheels carried by the corresponding frame, motion-transmission means from the protractor to 115 the frames whereby the registering wheels are caused to move radially on the disk when the protractor is turned, said motion-transmission means including means whereby one of the wheels is caused to move toward the center of rotation of the disk, while the other is moved away therefrom, means for indicating the number of revolutions of the disk, and means for indicating the number of revolutions of each of the registering wheels. 120
8. In a machine of the class described, a protractor mounted to turn in a horizontal plane, a disk mounted to revolve in the horizontal plane and co-axial with the protractor, said disk having means for indicating distance, registering wheels mounted to revolve in vertical planes and frictionally engaging the disk, the diameter of the registering wheels bearing a predetermined ratio 125 to the diameter of the disk, a gravitationally-operable frame for each of said registering wheels whereby the frictional engagement is maintained between the registering wheels and the disk, said registering wheels having divisions on the periphery thereof corresponding to the divisions of the disk, a vernier for said registering wheels carried by the corresponding frame, motion-transmission means from the protractor to 130 the frames whereby the registering wheels are caused to move radially on the disk when the protractor is turned, said motion-transmission means including means whereby one of the wheels is caused to move toward the center of rotation of the disk, while the other is moved away therefrom, means for indicating the number of revolutions of the disk, and means for indicating the number of revolutions of each of the registering wheels. 130

center of rotation of the disk while the other is moved away therefrom, means for indicating the number of revolutions of the disk, and means for indicating the number of 5 revolutions of each of the registering wheels.

7. In a machine of the class described, a protractor mounted to turn in a horizontal plane, a disk mounted to revolve in the horizontal plane spaced from the protractor and 10 provided with divisions for indicating distance, registering wheels disposed at right angles to each other and mounted to revolve in vertical planes and in frictional engagement with said disk, and motion transmis-

sion means from the protractor to the wheels 15 for displacing said wheels radially on the disk, the motion-transmission means including means for displacing one of the wheels toward the axis of rotation of the disk while the other is displaced away from the axis 20 of rotation.

In testimony whereof I have signed my name to this specification in the presence of two subscribing witnesses.

JOHN F. BENSON.
